United States Patent Office

Des. 202,006
Patented Aug. 17, 1965

202,006

BAR OF SOAP

Gladys R. Slipian, 5828 Nashville Ave., St. Louis, Mo.

Filed Sept. 14, 1964, Ser. No. 81,697

Term of patent 14 years

(Cl. D73—1)

I claim:

The ornamental design for a bar of soap, substantially as shown.
